UNITED STATES PATENT OFFICE.

FREDERICK A. HUBEL AND FRANK REINHOLD, OF DETROIT, MICHIGAN;
SAID REINHOLD ASSIGNOR TO SAID HUBEL.

MACHINE FOR GREASING CAPSULE-MOLD PINS.

SPECIFICATION forming part of Letters Patent No. 311,659, dated February 3, 1885.

Application filed January 15, 1883. (No model.)

To all whom it may concern:

Be it known that we, FREDERICK A. HUBEL and FRANK REINHOLD, of Detroit, in the county of Wayne and State of Michigan, have 5 invented new and useful Improvements in Capsule-Mold-Greasing Machines; and we hereby declare that the following is a full, clear, and exact description thereof, reference being had to the accompanying drawings, which form 10 a part of this specification.

This invention relates to that class of machines which are employed in the manufacture of gelatine capsules, and its specific purpose is to facilitate the lubrication of the mold-pins—a step in the process of manufacturing such capsules preceding the dipping of the pins into the gelatine.

In a recent application which we have made we describe the use of the band or ribbon as 20 a medium for transferring the lubricant to the pins, and in the present application we use the same medium, but the mode of so using it is entirely different, compelling an entirely different change in the construction of 25 the machine, and such changes in construction are noted in this application, being principally as follows: first, the mold-pins are kept stationary while the bands are drawn tightly around them, so as to rub the pins, and there- 30 by deposit a sufficient amount of lubricant, first upon one side and then upon the other; second, the greasing-rack is easily detached and adapted to be shifted laterally; third, a combination of devices for lubricating the pins 35 all around at one operation.

Figure 1 is a front elevation of our machine with the mold-plate and its standard withdrawn, showing, however, the mold-pins in their relative position, so as to illustrate the 40 operation of the device. Fig. 2 is a horizontal section of Fig. 1. Fig. 3 is a rear elevation of the machine. Fig. 4 is a side elevation thereof, partly in vertical section.

In the accompanying drawings, which form 45 a part of this specification, A is the bed-plate supporting the standard B, which is adapted to be reciprocated thereon between the guides b. Rising from the rear of the bed-plate, and securely connected thereto, is the vertical bed-

plate C, which is provided upon its front face 50 with a series of dovetail recesses, into which are fitted the bars D, adapted to be raised or lowered therein, and held in position, when not forcibly displaced, by the springs E, which press upon the opposite ends of each bar. 55 This position is shown in Fig. 1, where, however, one bar is shown forcibly depressed. The springs E may be provided with any of the usual devices for adjusting their tension.

Far a series of fingers, either round, square, 60 or in roller form, as shown in the drawings. Each bar D carries a vertical series of such fingers projecting horizontally therefrom, and when the bars D are not forcibly acted upon these fingers arrange themselves automatically 65 in horizontal series, and then they correspond as to distances apart exactly with the pins of the gelatine mold-plate G, for which the machine is designed.

F' F' are two additional vertical series of 70 fingers. They are attached outside the fingers F to the vertical bed-plate C, and are therefore stationary.

Attached to the rear face of the bed-plate C is the plate H, into which is cut the endless 75 groove I.

J is a friction-roller attached to the opposite end of the wrist.

M is a link, one end of which is pivotally attached to the lower end of the lever K, while 80 its other end is pivotally attached to the bed-plate C. Each of the bars D has attached to its rear face a wrist, N, which projects through a slot, O, in the vertical bed-plate C, and has secured upon its end a double cam-plate, P, 85 as shown in Figs. 3 and 4.

R is a rectangular rack, which holds in position a series of bands or ribbons, S, which are impregnated with the lubricant. Their ends are secured to clamping devices T, which 90 in turn are secured to the rack by means of shanks c, which pass loosely through the sides of the rack, and have secured on their ends a tension device, which in the drawings consists of a coil-spring, d, and nut e. The greasing-rack is kept in position upon the device by a guide, f, upon its lower side, which rests in a groove upon the bed A, and set-screw u, which

bears upon its upper side, this mode of fastening it in place allowing it to be easily shifted laterally, or removed and replaced by another.

In practice, the parts being arranged as described, and shown in the drawings, a mold-plate, G, is slipped into the standard B, as shown in Fig. 4, and then advanced so as to bring its mold-pins g between the bands S. The relative position of the pins g, bands S, 10 and fingers F and F' is shown in Fig. 1, (except as to one vertical series of fingers, F, which is forcibly depressed.) Each horizontal series of mold-pins lies between two bands, and the fingers F are in alternating horizontal 15 series between them and the bands. Now, the lever K, which works with its wrist in the groove I, is actuated so as to make its wrist traverse the entire groove from one end to the other, first through its upper and then back 20 through its lower bend. During this operation the cams P, and thereby the bars D and finger F, have been successively depressed and then successively raised, drawing thereby first those bands which lie on top of the mold-pins 25 down over their upper halves, and then those below the mold-pins up and around their lower halves. As the bars D are only depressed one after another, the mold-pins are all lubricated with the same tension upon the bands, 30 lubricating them thereby all uniformly. The fingers F' serve mainly as guide-pins for the bands S. In Fig. 1 one of the bars D is depressed, showing how this depression draws the top band down over the pins, rubbing (so 35 to speak) the band over it, first one way and then rubbing it again the reverse way, owing to the action of the springs E, which bring each bar back to its original position after the lever K has moved over its cam. One oscillation of the lever will lubricate all the mold-pins of one plate sufficiently for the purpose. 40 Different machines may easily be devised for carrying out the spirit of our invention, which simply consists in the manner of lubricating the pins by drawing the greased medium over the pins, in contradistinction from bringing it only in contact therewith, as in our former machine, where the mold-pins have 45 to be rubbed upon the medium to deposit the 50 lubricant properly.

What we claim as our invention is—

1. In a machine for greasing capsule-molds, the combination of a mold-plate, a movable support adapted to carry said mold-plate, a series of greased ribbons held by elastic attachments in a frame, and mechanism adapted to force successive portions of said ribbons out of their normal planes, substantially as and for the purpose specified. 55

2. In a greasing-machine for gelatine-capsule-mold pins, the combination of the detachable greasing-rack, upon which the lubricating-bands are stretched, with said bands and suitable tension devices, substantially as described. 60

3. In a greasing-machine for gelatine-capsule-mold pins, the bars D, arranged to move in guides, and provided with fingers F in vertical series, in combination with devices for successively depressing the same, substantially 70 as and for the purpose described.

4. In a greasing-machine for gelatine-capsule-mold pins, the finger-bars D, held in middle position by the springs E E, acting upon their upper and lower ends, and in combination with devices for depressing and raising the same successively for the purpose of drawing the lubricating medium over the upper and lower halves of the mold-pins, substantially as described. 75

5. In a greasing-machine for gelatine-capsule-mold pins, the greasing-rack provided with a series of bands with tension devices, and in combination with actuating-fingers F, arranged in horizontal series below and above 85 each set of two ribbons, substantially as and for the purposes specified.

6. As a means for raising and lowering the finger-bars D, and in combination therewith, the grooved plate H, lever K, wrist J, and cams P, substantially as and for the purpose specified. 90

F. A. HUBEL.
F. REINHOLD.
